UNITED STATES PATENT OFFICE.

IRA T. SWARTZ, OF INDIANAPOLIS, INDIANA, ASSIGNOR TO SWARTZ ELECTRIC COMPANY, OF INDIANAPOLIS, INDIANA, A CORPORATION OF INDIANA.

ELECTROMAGNETIC THROTTLE GOVERNOR.

Application filed November 17, 1919. Serial No. 338,751.

To all whom it may concern:

Be it known that I, IRA T. SWARTZ, a citizen of the United States, residing at Indianapolis, in the county of Marion and State 5 of Indiana, have invented certain new and useful Improvements in Electromagnetic Throttle Governors, of which the following is a specification.

This invention relates to throttle governors adapted for use with internal combustion engines, more especially to an electromagnetically operated throttle governor of a type wherein a movable plunger is operatively connected to the throttle valve and is actuated by fluctuations in the voltage generated in a dynamo electric machine cooperating with the internal combustion engine. My present invention constitutes an improvement over the device described and 15 claimed in my co-pending application, Serial No. 315,190, filed August 4, 1919, on throttle governors, it being among the objects of this invention to produce a governor which is more sensitive and reliable, which 20 will not allow the engine to run away, and which gives steadier operation of the electric power system in which it is inserted.

Hitherto considerable difficulty has been encountered in eliminating the "blink" or 30 flickering of the lamps on a circuit which is being supplied by a dynamo operated by an internal combustion engine. Such blink is largely due to the fluctuations in the engine's speed, especially at the lower speeds, and the governor disclosed in the above mentioned application in a large measure overcomes such fluctuations, and also fluctuations or accidental stopping of the engine due to a sudden demand on the generator which 35 40 momentarily robs the voltage governor of energy allowing the governing mechanism to shut the throttle and "kill" the engine.

My present invention more perfectly eliminates the fluctuations due to the above 45 mentioned causes and equalizes the engine's speed by a comparatively simple device. In carrying the objects of my invention into effect, I provide a specially constructed plunger having means thereon for better controlling the throttle opening. Specifically, my 50 invention comprises a plunger the movements of which are controlled by a solenoid having a hollow central portion; a plunger rod fits into this opening and has a spring on the 55 lower end contacting with the under side

of the plunger and with a washer held by a nut threaded on the lower end of the plunger rod. The upper end of the plunger rod at a point a short distance above the top of the plunger is articulated to allow it 60 to move eccentrically in performing its governing function.

Referring to the accompanying drawings forming a part hereof and in which similar reference characters denote similar parts. 65

The single figure illustrates a vertical section through my improved governor, some parts being shown in elevation.

The casing 1 of the governor carries a shaft 2, one end of which is connected to the 70 throttle valve of the engine and the other end connects to the governor mechanism by adjustable means 3, and a cover plate 4 is provided to allow of ready access for adjustment purposes. A solenoid 5 is fixed in 75 the lower portion 6 of the casing and is connected to the dynamo operated by the engine in a well known manner. The inner portion of the solenoid is closely fitted with a cylindrical casing 7 within which the plunger 8, whose movements are controlled by the solenoid 5 is adapted to move.

A central opening 9 is formed in the plunger, in which opening a plunger rod 10 is 80 closely fitted to allow of relative motion of plunger and plunger rod. The lower end 11 of the rod is threaded to receive a nut 12 upon which a washer 13 rests, the washer serving as the lower support for a spring 14 inserted between the washer and the lower 85 end 15 of the plunger. The upper end of the plunger rod is jointed at 16, preferably at a point just above the upper end of the plunger, in order to allow the portion 17 of the plunger rod to move eccentrically on its 90 pivot 18 in controlling the movements of the 95 throttle valve.

The governor is initially set by hand, as described in my co-pending application above referred to, the engine started, and 100 the dynamo allowed to "pick up" voltage. The solenoid 5 is energized, acting upon the plunger 9 in such a way as to hold the throttle valve in its proper open position. Should there be a sudden drain or demand upon the 105 system, or a small amount of dirt momentarily block the opening of the carburetor needle valve, there is a tendency for the plunger to drop and cut off the throttle.

By the present arrangement should a con- 110

tingency such as this occur, and the voltage in the solenoid 5 suddenly decrease, the plunger 8 will fall, but in falling will compress spring 14 to a considerable extent before the falling motion is transmitted through the plunger rod which in turn tends to close the throttle valve. If such loss of voltage is only momentary the plunger will be immediately drawn back into its proper position without having transmitted its accidental downward motion to the throttle valve. It will be seen therefore that accidental and momentary fluctuations do not affect my improved throttle governor, giving a steadier operation of the electric power system.

Having thus fully described my said invention, what I claim as new and desire to secure by Letters Patent, is—

- 20 1. A throttle governor comprising a casing, a horizontal throttle shaft in the casing, a rockarm on the shaft, a hollow cylinder supported by the casing below said crankpin and closed at its lower end, a stationary electromagnet about said cylinder, an armature fitting loosely in the cylinder, a rod 25 extending loosely through the armature, a cushioning spring between the armature and

the lower end of the rod, a connecting rod between the crankpin and the first-named rod, the joint between said rods being enlarged adjacent the upper end of the armature whereby the throttle shaft may be positively moved to-and-fro by the movements of the armature, substantially as set forth. 30 35

2. In a throttle governor for engines, means for preventing momentary fluctuations comprising a rockshaft connected to the throttle valve, a rockarm fixed to the shaft, a solenoid in circuit with a dynamo operated by the engine, an armature connected to said arm arranged to be moved in one direction by the solenoid and in the other by gravity, and a spring in the connections between the armature and the rock-arm to prevent sudden closing of the throttle on temporary failure of the solenoid, substantially as set forth. 40 45

In witness whereof, I have hereunto set my hand and seal at Indianapolis, Indiana, this 14th day of November, A. D. nineteen hundred and nineteen.

IRA T. SWARTZ. [L. s.]
